UNITED STATES PATENT OFFICE

JOHN C. SHERMAN, OF GORHAM, MAINE

RAZOR AND PACKAGE OF BLADES

Application filed September 23, 1927. Serial No. 221,502.

This invention relates to an improved safety razor for use with a novel package of blades, the combination being such that old blades may be removed from the 5 razor and replaced by fresh ones without the necessity of touching either the discarded or fresh blades with the fingers. To this end, the razor is provided with manually releasable catches by which a blade can be picked 10 up or released without the fingers of the operator coming in contact with the blade. If desired, the cap of the razor which holds the blade in place may be of sufficient length to project beyond the ends of the blade so that 15 it may be grasped and removed without the fingers touching the blade, so as to obviate the danger of cutting the fingers on the blade.

The invention also includes a holder for 20 fresh blades adapted to hold a plurality of blades with spacers to facilitate the operation of catch elements on the razor for picking up a blade.

For a more complete disclosure of my invention, reference is had to the description 25 thereof which follows, and to the drawings, of which,—

Figure 1 is a perspective view of the several parts of a safety razor embodying the invention.

Figure 2 is a perspective view of a package 30 of razor blades which is supported on my improved holder.

Figure 3 is a section of an assembled razor showing the relation of the various parts.

Figure 4 is a section on a larger scale of a 35 portion of the razor showing how a blade is picked up from the package.

Referring to the drawings in detail, 40 10 represents the handle portion of a safety razor of a well known type. To this handle portion is secured a guard 11 having perforations 12, 13, 14 therethrough to receive respectively positioning pins 15, 16, 17 of a cap 18, between 45 which and the guard 11 a blade 19 may be clamped. The blade 19 is also perforated as at 20, 21, 22 to permit the pins 15, 16, 17 to pass therethrough. These pins are customarily arranged in a line and the middle pin 16 is threaded so that when it is inserted 50 through the perforation 13 and enters the

hollow handle 10, it may be engaged by an elongated cylindrical nut 23 which extends through the handle 10 and is provided with a knurled end piece 24. When the nut 23 is inserted in the handle 10, a shoulder 25 formed by the knurled end portion 24 engages the end of the handle 10 so that when the threaded pin 16 is inserted through the aperture 13 and is engaged by the internal threads of the nut 23, the cap 18 may be drawn up 55 tightly against the guard 11 by turning the finger piece 24. Heretofore the cap 18 has been made shorter than the blade 19, so that the ends of the latter will project beyond the cap and will enable the user to grasp the ends 60 of the blade with the fingers when removing the blade from the razor. According to my invention, I may make the cap 18 longer than the blade 19, so that the ends of the cap will project beyond the ends of a blade in position, and the cap may be removed without 65 touching the blade. In order to hold the blade 19 against the guard 11 independently of the cap 18, I provide a pair of members or catches 26 which as shown in Figure 1 are arranged to project through the perforation 13 of the guard 11 and to extend through the perforation 21 of a blade 19. These members 26 are adapted to engage edge portions 70 of an aperture or apertures in a blade in a manner to grip the blade. The members 26 may, if desired, be hooked and may be normally pressed outwardly away from each other by any suitable means so that after passing through the perforation 21 of the blade, 75 they will catch on the further face of the blade and hold it against the guard 11. To this end, the catches 26 may be mounted on spring members attached directly to the handle 10 or the guard 11, or as shown they may be pivotally attached to the handle 10 as at 80 27, suitable springs 28 being employed to press the catch members outwardly. It is to be understood that the term "catches" as applied herein to the members 26 is used by way of illustration and not limitation, and that it includes any members movable to engage edge portions of a loose blade to grip 85 and hold the same. The threaded pin 16 is 90 preferably channeled as at 29 to receive the 95 100

catches 26 so that the pin 16 may enter the perforation 13 without being obstructed thereby. The inner face of the cap 18 is also recessed as at 30 to receive the ends of the catch members 26 and to permit the cap to lie directly against the surface of the blade 19. When removing a blade from the razor, the razor is preferably held with the guard 11 above the handle 10 in the position shown in Figure 1. The member 23 is unscrewed by manipulating the finger piece 24 and may be removed from the handle. This frees the cap 18 which may be then lifted off. The handle and guard may then be inverted, the blade 19 being held by the catches 26. The blade may then be dropped into any suitable receptacle for used blades by holding the guard over the receptacle and pinching together the catches 26 by pressing their supports with the fingers against the springs 28. Thus a used blade may be readily removed from the razor without the blade being touched by the fingers of the operator. In order to insert a new blade or a fresh blade in the razor without touching the blade with the fingers, I provide a special improved package of blades to cooperate with the catch members 26. As shown in Figure 2, the blades 19 may be separated by spacing members 31 which may be of paper or any convenient substance of sufficient thickness to enable the catching points of the catch members 26 to enter between successive blades after being inserted through the perforation 21 of the top blade of the package. The spacers 31 may be perforated or otherwise arranged to allow clearance around the perforations 21 of the blades so that the spacers themselves will not interfere with the catch members 26. In order to hold a package of blades conveniently, I provide a holder comprising a base member 32 from which project a pair of pins 33, 34 spaced to enter the outer perforations 20, 22 of the blades 19 of a package. When it is desired to insert a new blade in the razor, the guard 11 may be brought down in contact with the top blade of a package, the pins 33, 34 entering the apertures 12, 14 in the guard 11. This guides the catches 26 to the perforation 21 of the blade. These catches being pressed together may be inserted through the perforation 21 of the top blade and released so as to engage the lower surface of the blade. When the handle 10 and guard 11 are now raised, the top blade 19 will be picked up by them. The cap 18 may be thereupon placed against the blade, the member 23 inserted in the handle, and the razor set up for use in the usual manner.

By this construction, I have made it possible to remove a blade from the razor and to insert a fresh blade easily and quickly without touching either blade with the fingers.

Having thus described certain embodiments of my invention, it should be evident

to those skilled in the art that various changes and modifications might be made therein without departing from its spirit or scope as defined by the appended claims.

I claim:

1. A safety razor comprising a perforated guard, a cap having holding pins adapted to project through a blade and to enter the perforations of said guard, one of said pins having longitudinal grooves in the sides thereof, and yielding catches extending through one of said perforations and adapted to releasably hold a blade against said guard, said catches being arranged to enter said grooves when the pins on the cap enter said perforations.

2. A safety razor guard having catch elements arranged to pass through a perforated blade and to catch on the further face, in combination with a package containing a perforated blade and a spacing element thereunder providing clearance about one of said perforations to permit the entrance of said catch elements.

3. A safety razor guard having three perforations therethrough arranged substantially in line, and having catch elements associated therewith, in combination with a blade holder having a base, a pair of pins projecting from said base and spaced to enter the outer two of the three said perforations and thus to receive a blade having perforations corresponding to those in the guard, and spacing means for holding a blade above said base arranged to provide clearance about one of said perforations of the blade thereon for the reception of said catch elements.

4. A safety razor having a guard, a cap between which and said guard a blade may be clamped, and means operable to pick up with said guard a loose blade and to release a blade from said guard, said pick-up and release means including catches adapted to project from the guard beyond the remote face of the blade to be picked up and to engage on said remote face.

5. A safety razor comprising a perforated guard, a cap having holding pins adapted to project through a blade and to enter the perforations of said guard, said pins having among them a pair of longitudinal grooves in the sides thereof and a pair of yielding catches extending through said perforations and adapted to releasably hold a blade against said guard, said catches being arranged to enter said grooves when the pins on the cap enter said perforations.

6. A safety razor comprising a blade having outer and inner edge portions, a perforated guard, a cap between which and said guard said blade may be clamped, and means for drawing said cap into clamping engagement with said guard, said razor also including means engageable with certain of said edge portions and operable to pick up a blade

with said guard and to release a blade from said guard.

7. A safety razor having a guard, a cap between which and said guard a blade may be clamped, and means operable to pick up with said guard a loose blade and to release a blade from said guard, said pick-up and release means including elements to engage edge portions of a blade and to grip said portions

10 to pick up the blade with said guard.

8. A safety razor comprising a blade, a guard, a cap between which and said guard said blade may be clamped, said cap projecting beyond both ends of said blade when the 15 parts are in normal position, and means for drawing said cap into clamping engagement with said guard, said razor also including means operable to pick up with said guard a loose blade and to release a blade from said 20 guard, said pick-up and release means including elements to engage edge portions of a blade and to grip said portions to pick up the blade with said guard.

In testimony whereof I have affixed my 25 signature.

JOHN C. SHERMAN.
